DESIGN FOR A FINGER RING OR SIMILAR ARTICLE

Herman B. Sacks, New York, N. Y.

Application October 6, 1943, Serial No. 111,283

Term of patent 3½ years

To all whom it may concern:

Be it known that I, Herman B. Sacks, a citizen of the United States and resident of New York city, in the county of New York and State of New York, have invented a new, original, and ornamental Design for a Finger Ring or Similar Article, of which the following is a specification, reference being had to the accompanying drawing, forming part thereof, and in which, the sin-

gle figure is a perspective view of the finger ring, embodying my new design.

The settings and ornamentation shown on the partially disclosed outer periphery of the ring are repeated on the portion not shown.

I claim:

The ornamental design for a finger ring or similar article substantially as shown and described.

HERMAN B. SACKS.
